UNITED STATES PATENT OFFICE

CHESTER L. DAVIS, OF WASHINGTON, DISTRICT OF COLUMBIA, ASSIGNOR TO WIRED RADIO, INC., OF NEW YORK, N. Y., A CORPORATION OF DELAWARE

THERMIONIC TUBE

Application filed January 29, 1929. Serial No. 335,860.

My invention relates to thermionic tubes in general and more specifically to thermionic tubes of the type employed in signaling systems.

5 An object of my invention is to provide a thermionic tube wherein the anode space charge is reduced and the efficiency of the tube thereby increased.

10 A further object of my invention is to provide a thermionic tube whereby the anode space charge is reduced without changing the usual number of connections leading from the electrodes of said tube.

15 A still further object of my invention is to provide a thermionic tube wherein the anode has a negligible space charge effect.

20 Other and further objects of my invention are to provide certain structural features, a better understanding of which can be had from the specification following and from the accompanying drawing, wherein:

25 Figure 1 is an illustration showing one form of the anode employed in the thermionic tube of my invention; Fig. 2 is an illustration showing a form of the anode employed in the thermionic tube of my invention and Fig. 3 is an illustration showing schematically the thermionic tube of my invention.

30 In Fig. 1, the anode 1 consists of a metallic plate of nickel or other suitable metal or alloy thereof. A screen 2 is spacially related to the anode 1 and extends substantially parallel thereto. Screen 2 may be of any

35 suitable metal such as nickel or the like and may be in the form of a grid instead of the screen as shown. The word "screen" herein-after referred to is interpreted according to its operation which is to "screen" or "shield"

40 and it is to be understood that the same may be in the form of a grid. Screen 2 is rigidly positioned and spacially related to anode 1 by means of members 3, 4, 5 and 6. Members 3, 4, 5 and 6 may be of suitable material

45 or composition depending upon the type and size of tube. The resistance of members 3, 4, 5 and 6 are such as to supply the proper potential to screen 2, when the rated potential is supplied to anode 1. This potential should be lower than that supplied anode 1

which drop of potential is effected by the composition of the members 3, 4, 5 and 6. Suitable resistance materials include carbon or graphite which materials may be combined with other elements or materials whereby the resistance will be of proper value for the particular type of tube employed. Many variables enter into the design of such tubes including the degree of vacuum, the electronic emission of the cathode, the spacial relation of electrodes and the area of the electrodes. The composition of members 3, 4, 5 and 6 as well as the design of screen 2 as to number of wires and area depend upon these variables which must be considered in the design of the tube for maximum efficiency.

Fig. 2 of the accompanying drawing shows a modified form of my invention. In the modification illustrated in this drawing, 70 resistance member 7 serves a purpose similar to that of members 3, 4, 5 and 6. In this modification the screen is not supported from anode, as was the case in Fig. 1. Screen 12 is supported from stem 8 which 75 also supports anode 14, cathode 9 and control electrode or grid 10. The conducting wires 14a, 9a and 10a lead through base 11 and are connected to prongs 14b, 9b and 10b. Resistance element 7 may take the form of 80 an impregnated material in which case the impregnation may be that of carbon, a metal, allow of metals or oxide thereof. Resistance element 7 may be a wire wound resistance if desired. A metallic band 14c encircles 85 the stem 8 and provides a mechanical support for anode 14. Member 7a extends laterally from band 14c and provides both a mechanical support and an electrical connection for resistance 7. The upper end of 90 resistance 7 is mechanically supported and electrically connected to screen 12 through member 7b. Envelope 11a encloses all of the electrodes.

Fig. 3 of the drawing illustrates schematically the circuit arrangement of the electrodes in the thermionic tube illustrated in Fig. 2. The operation and advantages of the thermionic tube of my invention will be readily apparent from a consideration of 100

Fig. 3. If a source of electrical energy is connected to terminals 9b, cathode 9 emits electrons. These electrons are transmitted in all directions from cathode 9. If a source of electrical energy is connected between terminals 9b and 14b a potential difference exists between electrodes 9 and 14. If the positive polarity of the source is connected to anode 14 and the negative polarity of the source connected to cathode 9 the electronic stream from cathode 9 to anode 14 will be increased. In operation however it is true that a number of these electrons never reach the anode 14. Should these electrons reach anode 14 the electronic stream would be increased and hence the resistance of the tube considerably decreased. Screen 12 is positioned adjacent anode 1 in such manner as to cause these electrons to be further attracted to anode 14. This action of screen 12 is due to the positive polarity of the screen 12 with respect to the polarity of cathode 9. The potential difference between screen 12 and cathode 9 is less than the potential difference between anode 14 and cathode 9. Screen 12 directly associated with anode 14 may be considered as an integral part of anode 14 increasing its efficiency. It is obvious that a low potential is necessary for the operation of the thermionic tube of my invention as compared to the usual type of triode tube. The number of lead in wires to the elements are, however, the same as the triode. This feature makes the wiring less complicated. The lead from such an electrode as screen 12 if insulated from anode 14 and carried through the base of the tube, must be carefully shielded from stray fields.

40 The thermionic tube of my invention may be employed as an oscillator or amplifier in high frequency signaling systems. Water cooled tubes may be constructed wherein the anode is provided with a screen electrode according to my invention. The capacity of the tube is much less than that where a separate wire leads through the base for supplying the screen electrode potential.

I realize that many modifications of my invention are possible without departing from the spirit of my invention and it is to be understood that my invention is not limited by the foregoing specification or by the accompanying drawing but that modifications may be made within the scope of the appended claims without departing from the spirit of my invention.

What I claim as new and desire to secure by Letters Patent of the United States is as follows:

60 1. An electron tube comprising an enclosing envelope, a cathode, a control grid and an anode mounted therein, a resistance element carried by said anode and a shield grid supported by said resistance element in

spacial relation to said anode and between said anode and said control grid and disposed in an electrical path to receive a predetermined charge from said anode through said resistance element.

70 2. An electron tube comprising an enclosing envelope, a cathode, a control grid and an anode mounted therein, a plurality of resistance elements carried by said anode and a shield grid bridged between said resistance elements in a position spacially related to said anode and disposed between said anode and control grid, said resistance elements forming a conductive path for impressing an electrical potential on said shield grid in proportion to the drop along said resistance elements from the potential of said anode.

75 3. An electron tube comprising an enclosing envelope, a cathode, a control grid and an anode mounted therein, said anode including a pair of side plate portions extending substantially parallel to each other, a plurality of laterally extending resistance members separating said pair of side plate portions, and a shield grid supported by said resistance members in spacial relation to said anode and control grid for receiving a charge from said anode in proportion to the electrical drop along said resistance members from said anode.

80 In testimony whereof I affix my signature.
CHESTER L. DAVIS.
